UNITED STATES PATENT OFFICE

HARRY H. HARNSBERGER, OF CROTON-ON-HUDSON, NEW YORK, ASSIGNOR TO THE TURNAPAGE COMPANY, INC., OF NEW YORK, N. Y., A CORPORATION OF NEW YORK

NOTEBOOK HOLDER

Application filed July 3, 1924, Serial No. 724,065. Renewed February 9, 1931.

This invention relates to note book holding devices, and more particularly refers to devices suitable for holding short-hand note books or similar copy, used in connection with 5 typewriting machines.

The main object of this invention is to provide a device of the character stated, having novel and improved means for feeding the sheets of the note book as used, the action 10 of said feeding means being more positive and reliable than that obtainable by other devices heretofore in use.

Another object of this invention is to provide a copy holder, particularly adapted for 15 use in connection with short-hand note books, composed of members telescoping one within the other, and affording a collapsible, yet rigid support for the note book, adapted to be permanently installed at the rear of a typewriter, even if the typewriter is mounted on 20 a drop type desk.

A further object is to provide a copy holder the construction of which is such as to permit 25 ready insertion and removal of a note book such as used by typists for taking short-hand notes, without impairing the rigidity of the holder itself.

A still further object is to provide novel 30 and improved means for mounting the short-hand book, for the purpose of inserting it in the note book holder so as to be securely held in the proper position for the gradual feeding of its sheets on the part of the operator.

With these and other objects in view, as will 35 more clearly appear as the description proceeds, this invention furthermore comprises certain novel and improved constructions and arrangements of parts as will be hereinafter fully described and claimed in the appended 40 claims.

This invention represents an improvement on the class of devices stated, and is more particularly directed towards the improving of 45 a number of features described in connection with another device of a similar character, forming the object of a co-pending application for patent entitled book supporting device, filed by me June 30, 1922, Serial No. 571,914.

In said application I have described a de-

vice intended for practically the same purpose, embodying a number of features which in practice I have found to be susceptible of further improvement; and these improvements, which are mostly directed towards 53 rendering the operation of the device more positive and reliable, and partly towards increasing the strength and rigidity of the device, have been embodied in the present invention, and co-operate with each other in 58 greatly improving the performance of the device as a whole, and in extending the field of 63 its applications.

In order to facilitate understanding of the 65 novel features mentioned, I shall proceed with the description of the device illustrated in the annexed drawings, and shall particularly point out their advantages as the several points will be reached in the course of 70 the description.

The drawings illustrate the preferred embodiment of my invention, as used in connection with ordinary short-hand note books; however, the said drawings must be considered as being intended for illustrative purposes only, and not in a limiting sense, because many of the details of construction may 75 vary from those shown; and also because, although the device illustrated is particularly suitable for use in connection with stenographer's note books, it may be built in various sizes, and its use may be extended to 80 books of different character and size.

It may also be stated, that while the usefulness of the device is the result of a number of 85 contributory elements and features, some of these advantageous features may be applied singly or in combination to other similar devices, to improve their performance; therefore these important features will be particularly pointed out, and claimed per se in the 90 appended claims.

Referring to the drawings:

Fig. 1 is a side view in elevation of my device in its extended position, at the rear of 95 a typewriting machine;

Fig. 2 is a front view in elevation of the same;

Fig. 3 is a side view in elevation of the same from the opposite side;

Fig. 4 is a side view in elevation of my device in its inoperative position at the rear of a typewriting machine;

Fig. 5 is a plan sectional view through line 5—5 of Fig. 4;

Fig. 6 is a fragmentary side sectional view in elevation of a drop type desk, in which a typewriting machine is mounted in the ordinary manner, provided with my device at the rear, showing the possibility of closing the desk without hinderance;

Fig. 7 is a fragmentary plan view in elevation showing one of the ways of securing a note book to its carrier previous to insertion on the book holder;

Fig. 8 is a fragmentary side view in elevation showing the device open, and illustrating the manner of inserting a note-book on the book holder;

Fig. 9 is a fragmentary front view in elevation illustrating the upper part of the device;

Fig. 10 is a fragmentary side sectional view in elevation through line 10—10 of Fig. 9;

Fig. 11 is a similar side sectional view in elevation through line 11—11 of Fig. 9;

Fig. 12 is a plan view of the device in its closed position; and

Fig. 13 is a fragmentary plan view of the same, with the casing in which the operating mechanism is mounted, thrown open for the insertion or removal of a note book.

The general appearance of my device in its preferred form, is illustrated in Figs. 1 to 4, and from these it may be observed that the same consists, essentially, of two main parts: a stand, 20, suitably mounted on a base plate 21 and secured thereto by means of an inclined brace 22, and a book holding member 23 slidably mounted on said stand so as to form a telescopic structure adapted to be maintained in its extended position, as shown in Fig. 1, or adapted to be caused to assume the inoperative or retracted position shown in Fig. 4, where one of the said parts overlaps the other.

One of the main objects of my invention, is to provide a note-book supporting device, carrying an operating mechanism for turning the leaves of the book, adapted to hold the book from which notes have to be transcribed, in full view of the operator, facing the operator directly, and at a distance calculated to suit an operator of normal vision, without causing eye strain. These conditions are of course aimed at, as the ones best insuring rapid and efficient transcription, and the same time inducing the least strain on the operator. Practical considerations also make it desirable for the device to be so constructed, as to be readily applied in connection with any type or make of typewriting machine, its setting up being practically independent of the typewriting machine itself.

I have therefore adopted the simple arrangement shown in the drawings, where the stand on which the device is supported is mounted on a base plate 21, made of sheet metal, and adapted to be placed with its forward portion 24 (Figs. 4 and 5) directly underneath the rear feet of the typewriting machine 25. In this manner, the device may be placed directly behind the typewriter, thus remaining at a convenient distance from the operator's eyes, and it may be held in this position by the weight of the typewriter; there being no necessity of using any other fastening means.

This is important, both on account of the avoidance of the use of screws or other fastening means which would be apt to mar the desk on which the device is placed, and on account of the ease with which the device may be placed in position or removed, in a few seconds. Furthermore, the very simplicity of this arrangement, is a contributing factor decreasing the cost of production.

A device intended for use in connection with a typewriter placed on top of a table or desk having a stationary surface, does not necessarily have to be of a collapsible construction; since when the device is in use, the book mounted thereon must be in full view of the operator, looking over and beyond the typewriter, as is shown in Fig. 1. However, typewriting machines are very often mounted on desks of the drop table type, where the machine may be caused to disappear under a movable portion of the desk top, when not in use, so as to permit the use of the desk unencumbered by the machine.

This type of desk, which is represented in Fig. 6, comprises a movable table 26, on which the typewriter 25' is mounted, pivotally mounted at the sides at 27, and operated by the raising or lowering of the movable desk top portion 28, in a well known manner. The figure represents the desk in the act of being closed, and from the same it may be seen that the movable top portion 28 passes fairly close to the upper part of the typewriter, so that it would be utterly impossible to close the desk, were the book-holding device held at the rear of the typewriter in its extended position.

For this reason, I prefer to make my device in two parts, one movable in relation to the other, and adapted to be set in such a position, when inoperative, that the operation of a drop type desk will not be interfered with.

In my co-pending patent application above-referred to, I have taken care of this requirement, by pivotally mounting the book-supporting member on a horizontal pivot at the top of the stand; this permitting to set the upper, or book-supporting member, in a downward, or folded position, over the top of the typewriting machine. Fur-

ther experience, however, has led me to believe the telescoping construction shown in the present drawings, to be preferable, being less apt to interfere with the typewriter, 5 and being simpler and easier to operate.

In said Fig. 4, my device is shown mounted in position at 29, at the rear of the typewriter, in its retracted position, allowing free operation of the desk, as illustrated.

10 The collapsible construction of the device is obtained, as stated, by causing one of its main parts to telescope within the other. In the present case, the lower member, or stand 20, is made in the form of plate embossed 15 with a shallow C section, best seen in Fig. 5, provided with two outwardly directed longitudinal flanges 30, 31. The upper, or book-holding member, comprises a plate 23, the edges of which are bent rearwardly and 20 inwardly at 32, 33, to slidably interlock with flanges 30, 31, respectively, so that a telescoping connection becomes established.

Plate 23 is reinforced at the rear by two longitudinal bars 34, 35, projecting within 25 the shallow depression of the C-shaped part 20. At the rear of said part 20, is mounted a spring controlled shaft 36, carrying two stop lugs 37, 38, tending to remain in the position shown in Fig. 3; so that when the 30 book-holding member is in its raised position, the lower edge of bars 34, 35, rests against the said stop lugs, and the device remains set in its extended position.

Shaft 36 is integral or provided with a 35 hand control lever 39, by means of which the shaft may be rocked in a clockwise direction. By so operating the shaft, stop lugs 37, 38, will move away from bars 34, 35, and the book-holding member will become free 40 to fall to its lower position, shown in Fig. 4, by the action of its own weight. Impact receiving means are preferably provided, to prevent unnecessary noise, or a too violent shock, when the book-holding member strikes 45 bottom; and a simple contrivance to this end is shown in Fig. 2 in the form of a bow spring 40 attached at 41 to plate 21, directly underneath the book-holding member, acting as a bumper absorbing the impact thereof.

50 A note-book 42 is suitably mounted on the book-holding member, as will be later specified, and set in operative position with respect to the operating mechanism. This consists, essentially, of a rotatable shaft 43, mounted across the top and in front of the exposed page 44 of the book, provided with one or more circular contact members 45, held with suitable pressure abutting against the surface of said page, and an operating 55 mechanism controlling the operation of said shaft. The relative positions of these parts is shown in Fig. 10, where it is seen that rotation of shaft 43 in a clockwise direction causes the outer leaf 44, against which members 45 abut, to move upwardly and fall over

the back of the device, thus exposing the next sheet 46 to view.

In the device forming the object of my co-pending application above-referred to, the contact member causing the gradual and successive feeding of the sheets or leaves of the note-book, is a rubber apron or belt, the motion of which is translatory rather than circular; but the character of the feeding means employed, is not to be limited to any particular type, since feeding means of various designs will answer; also, it may be here noted, the idea of feeding a sheet of paper by means of a rolling or traveling friction member, is, broadly speaking, not new.

The feature which is new, and important, in the arrangement adopted, is a way of mounting the feeding member insuring at all times a positive feed, in connection with a note-book of the character specified.

For a device of this character to be practical, it is necessary that all parts of a page become gradually exposed to view; therefore it is necessary, for the operating mechanism, to conceal as little as possible of the page underneath, so that the writing space may be utilized to best advantage. For this reason, the line of contact between the feeding member and the underlying leaf, is caused 95 to be quite at the top of the page, as shown, so that possibly only one or two lines at most of writing space at the top of the page will be left blank when taking notes.

However, ordinary stenographer's note 100 books, consist of quite a number of sheets folded together in a single fold, so that the pages at the middle of the book start at a point about one-quarter of an inch lower than the outer pages, or even more. As page after

page is turned over, the thickness of the book decreases, and since the feeding member must be maintained in constant contact therewith, it follows that the feeding member must be 105 made movable towards the book, that is, the contact must be maintained while the thickness of the book decreases. This may be assured in a number of ways, for instance by employing resilient means for creating the pressure necessary to create the necessary 110 frictional contact.

If the feeding member's position in relation to the underlying book, at the beginning of the operation, is such that the line of contact is about three-eights of an inch from the top of the page, as shown 115 in Fig. 4, and if in order to take up the differences gradually occurring in the thickness of the book, the feeding member is caused to travel right across in a transversal direction, when the middle of the book is reached, the feeding member is quite likely to abut 120 against the underlying page right at the folding line, or even above the binding clips or wires. The device will then have become 125 inoperative, since no pull will be exerted on 130

the sheet, which is substantially, or actually out of contact with the feeding member.

In the device described in my co-pending application above-referred to, the shaft of the feeding member is carried by a frame which is pivotally mounted to allow movement of the shaft from front to rear; but said frame is pivoted at a point above the shaft, and forward, so that when the shaft 5 moves against the book, it gradually assumes higher and higher positions. I have found this to be a very serious drawback to the efficient operation of the device, inasmuch as this feature still further accentuates the 10 tendency of the line of contact to gradually move to a point above the binding line, which I have just mentioned.

It is therefore important, that the feeding member be mounted in a way which will assure the line of contact with the underlying sheet, being permanently below the folding or binding line, so that the feeding of the sheets may proceed in a continuous and regular manner, from beginning to end.

This end may be achieved in a number of ways; but since the pivotal mounting of the frame carrying the feeding member offers a simple and convenient means of producing the desired result, I prefer to retain it in the 20 present device, but in a suitably modified form.

Accordingly, shaft 43 is mounted in a frame 47, which is pivotally mounted at 48, at a point above the book at the rear; so that as the thickness of the book decreases, the feeding member moves along a downwardly directed arc, and will cause the contact line to always remain past the binding point of any given sheet. To assist in the folding 30 back of the sheets, as they are gradually fed upwardly by the feeding member, the frame is preferably formed with a curved upwardly inclined front surface 49, gradually forcing the sheets towards the rear of the device, until free to fall back due to their own elasticity and weight. This action of surface 49 will become apparent by observing the outline of sheet 44 in Fig. 10.

The movement of the feeding member is always effected in the same direction, and its travel, and the extent thereof, each time that a portion of a sheet is caused to move upwardly, are preferably controlled by the operator, to suit his or her convenience. Therefore I provide a key operated controlling mechanism, and means for adjusting the range of its operation, the main objects in view being convenience of operation, and simplicity of design.

At this point also it may be stated that motion of the feeding member in one direction may be produced in a number of ways, as any competent mechanic well knows; by means of a controlling member actuated always in the 60 same direction, or by means of a member

movable in two opposite directions; or by any suitable mechanical expedient or means.

Together with a mechanical arrangement which I have selected on account of its simplicity, and which is admittedly susceptible of change in various directions, I have incorporated some features which I consider important apart from the mechanism itself, and which I consider to be new and integral part of this invention. 70

One of these features concerns the manner of controlling the operation of the device. In devices of this character, a key lever is ordinarily employed, pivoted on a horizontally crosswise pivot, and operated by striking the 80 key downwardly.

A key lever of this description is shown, for instance, in the drawings appertaining to my co-pending application, and while its operation is fairly satisfactory, I have found that the speed of the operator could be improved by adopting the form of control shown in connection with the present device. 85

By referring to Figs. 2, 4, 5, it will be observed that this arrangement comprises a horizontal shaft 50 mounted from front to rear alongside of the typewriting machine, carrying a hand control lever 51 mounted at its front end, upwardly directed at one side of the typewriter's keyboard. The operator 90 strikes this lever from time to time with the side of the hand, forcing the same outwardly, and therefore causing angular motion of the shaft. At the other end of the shaft, suitable means are provided for transmitting 95 this motion to the operating mechanism, as I will later describe, and spring means are also provided for returning the shaft and lever to their normal position.

In this manner, the operator is sure to strike the lever every time, simply by an extra side movement of the hand, entailing no necessity whatever of aiming at any particular point, or of exerting any special amount of attention; so that his or her attention remains concentrated upon the reading of the notes, and the operating of the typewriter 100 in the usual manner.

The extent of the motion of the feeding member, to which the movement of shaft 50 is ultimately transmitted, is determined by the extent of the angular motion of said shaft; therefore, by regulating the angular travel of the shaft, the amount of paper fed at each 110 stroke is accordingly regulated.

I provide therefore adjusting means of any suitable character, permitting lever 51 to move more or less, and a suitable arrangement to this end is illustrated in Figs. 2, 4, 5. In the same it is seen that shaft 50 carries a cross arm 52, provided with an adjustable screw 53, which strikes the surface of plate 21 when lever 51 is moved outwardly. By causing the stem of said screw to project more or less from the cross arm, therefore, 125 130

shaft 51 will accordingly be made capable of smaller or greater angular motion; and any such adjustment may be easily and readily effected.

5 Another one of the features above-referred to concerns the manner of applying the driving force exerted through the flexible element, to the feeding member. At a previous stage of this description I have mentioned 10 the possibility of employing resilient means for creating the pressure necessary to establish the required frictional contact between the feeding member and the underlying sheet, and in my co-pending application above-referred to I have described an arrangement embodying such a feature.

Upon further experience, however, I have found that this means of creating the necessary pressure, is apt to be not entirely satisfactory at all stages of the operation, unless 20 means are provided to counterbalance the effect of the variations gradually taking place in the thickness of that part of the note-book against which the feeding member abuts. 25 Such variations will naturally be reflected by variations in the pressure exerted by the spring or other means used, which may be suitable when a new book is inserted on the book-holder, but may become inadequate as 30 the thickness of the book decreases; or else, if suitable for the book when its last pages are being unfolded, may be found to be excessive at the beginning. In both cases the 35 results are unsatisfactory, inasmuch as insufficient pressure will interfere with the feed, which may cease altogether to take place on this account; and excessive pressure is liable to jam the book, creating a friction between the exposed sheet and one or more 40 of the underlying sheets, which may cause the outer sheet to pull up one or more of the underlying sheets at one time.

Now, it is obvious that the pressure must at all times be sufficient to feed the outer 45 sheet as the operator requires it; at the same time, said pressure must never be such as to cause the feeding of more than one sheet at a time. It would not be quite exact to state that the pressure should be uniform at all 50 times, because in fact more pressure is required for turning the pages as the book decreases in thickness, than is required at the beginning; but neither is it necessary to maintain the pressure exactly at a given 55 figure for each stage of the operation, there being naturally a certain leeway which may be taken advantage of in designing the device. In a general way it may be stated, that while it is desirable to cause the pressure 60 to increase as the thickness of the book decreases, yet it is not strictly necessary to do so; it is sufficient that the pressure exerted be at all times sufficient to feed the sheets offering the most resistance, in a reliable and continuous manner. If the pressure is limited to

this requirement, it is not liable to be excessive in an objectionable sense, when feeding the outer sheets.

In the construction shown in the drawings which I will presently explain, the pressure created does not even increase with the decreasing of the thickness; on the contrary, it decreases, the design of the arrangement having been influenced by other considerations. But in practice the result remains 70 that the pressure obtained is sufficient to operate the last pages of the book; it is perhaps a trifle excessive when the first few pages of the book are unfolded; but it is never objectionable in the sense of causing the feeding of more than one sheet at a time. 80

I attribute this result to the fact that while a spring is used, indirectly, to maintain the feeding member in contact with the underlying sheet, yet the actual frictional contact enabling the feeding member to transmit its motion to the sheet, is independent of said spring, and is caused by a force which is practically uniform throughout, such as might be caused by a vertically movable 85 counterweight.

Such force is exerted directly owing to the pulling action of the flexible element, which is transmitted to the feeding member in such a way as to first cause a tendency in said feeding member to press against the underlying page, and then to operate the feeding member when the resistance to this frictional transitory motion becomes sufficient to cause its termination. A double action is therefore performed by the force originally exerted by the operator, in first creating the necessary frictional contact, and then causing the feeding action to take place. 100

This result may be attained in various ways, but in a general sense it may be stated that it will follow a construction where the feeding member is mounted on a frame which is movable in relation to a point of support, and where the actuating force is applied to the feeding member in such a way as to tend to move the frame in the direction of the sheet to be fed, owing to the reaction induced in its point of support. 105

One of the embodiments of this principle is shown in the drawings, and may be observed by referring to Fig. 11. On account of considerations which I will point out at a later stage of this description, I prefer to use a pawl and ratchet mechanism for producing 115 the rotation of the feeding member. As previously explained, the feeding member comprises a shaft 43, which is rotatably mounted on a frame 47, which is in its turn pivotally mounted at 48 to the book-holding member. The natural tendency of the frame is to move downwardly, holding the feeding member against the surface of the underlying sheet 44. 120

At one end of shaft 43, externally to frame 125

47, is mounted a pinion 59, in mesh with a gear 60, loosely mounted on a stud 61 attached to said frame. Alongside said gear, on the same stud 61, is also rotatably mounted a drum 56, to which, as we have seen, the end of flexible element 54 is attached. Said drum has a hollow, within which is placed a helical spring 62, having one of its ends secured to stud 61 and the other to the peripheral surface of the hollow in said drum, said spring tending to cause rotation of said drum in a clockwise direction.

Said drum carries a pawl 63, engaging the teeth of gear 60 when said drum is caused to rotate in a counter-clockwise direction, but allowing the free rotation of said drum in relation to said gear, when the drum is rotating in a clockwise direction. Said pawl is maintained against the surface of the gear by a leaf spring 64.

A pull exerted on wire 54, obviously causes rotation of drum 56 in a counterclockwise direction, and this in its turn causes rotation of gear 60, and consequently rotation of pinion 59, shaft 43 and feeding member 45, in a clockwise direction. Rotation of member 45 in this direction, causes the feeding of the sheets, as previously explained.

However, it will be observed that stud 61 is eccentric to pivot 48. Any downwardly directed force applied to stud 61 will cause a turning moment of the frame around its pivot, causing the feeding member to press against the underlying surface.

It therefore can be seen, that a pull exerted on wire 54 in a downward direction, such as takes place upon the operation of lever 51, will create a tendency in frame 47 to rotate in a clockwise direction, since said pull may be considered the equivalent of a downwardly directed force applied against stud 61 through the intermediary of drum 56.

The desired condition of creating the necessary frictional contact, and producing the feeding action by means of the same force, is therefore realized by this comparatively simple arrangement. As stated before, the pressure exerted by the feeding member against the underlying surface decreases as the thickness of the book decreases, because the leverage of the pulling force becomes gradually smaller in relation to pivot 48; however, the difference between the two extreme positions of the feeding member due to the thickness of the book, is comparatively small, and does not influence the pressure exerted to any great extent. On the other hand, proper location of stud 61 in relation to pivot 48, will determine the amount of average pressure produced, and experience will furnish indications as to the best horizontal distance or leverage between 61 and 48, to be adopted in practice.

We have thus created a condition where

a practically uniform pressure is created against the pages of the book by the feeding member, as the feeding takes place, this pressure being, owing to the leverage adopted, the one best suited to produce a sufficient but not excessive frictional contact; in other words we have created a condition closely resembling the feeding by hand, where the thumb is first pressed against the surface of the sheet, and is then moved in the feeding direction, while the pressure is maintained.

The construction indicated, while not realizing a condition where the pressure is increased rather than decreased with the decreasing of the thickness of the book, is preferable for reasons of design, so as to preserve the compactness and small size of the device. It will be observed that if the combined weight of frame 47 and the feeding member carried thereby is sufficient to create the desired friction between the rollers and the underlying sheet, it may be unnecessary to add to this action the pressure exerted by the pull of the flexible element; therefore, in this case, the direction of application of the pulling force may be substantially in line with the pivot upon which frame 47 is mounted so as not to noticeably affect the pressure exerted by the pivotally mounted structure upon the sheet. Also in this case, while an auxiliary spring might also be employed, a fairly uniform pressure is obtained in an exceedingly simple manner.

The drawings also illustrate a very convenient manner of transmitting the motion of shaft 50 to the operating mechanism. Independently of the manner in which the feeding of the paper is effected, it is obvious that the connection between the shaft and the operating mechanism must be such as to allow the motion of the book holder relative to its stand, without hindrance, and without entailing the necessity of additional operations.

This applies whether the book-holding member is mounted to the stand by articulated connection, as shown in my co-pending application, or whether the connection is by telescoping arrangement, as in the present case. For the sake of simplicity, I prefer to use a flexible element controlled by shaft 50, and exerting a pull on the actuator of the operating mechanism when lever 51 is moved outwardly.

This flexible element, designated by numeral 54, is attached to a lever 55 integral with, or attached to shaft 50, at the rear, and participating of the angular motion of the shaft. Thus outward movement of lever 51 is transformed into a pull exerted on flexible element 54 by lever 55, said pull being in its turn transmitted to drum 56, to which the other end of flexible element 54 is attached, through the intermediary of an idle pulley 57, over which element 54 is caused to pass.

The flexible element must be inextensible as well as flexible, and must have a high tensile resistance, in order to provide continuous and reliable service; and for this purpose I prefer to use cat gut, such as used for musical strings, although metallic wire would also answer. However, it is necessary to prevent the possibility of the wire becoming entangled, or bent, or damaged, so as to preserve its flexibility, and so that the device may be operated at all times without delay. The new feature above referred to is intended to take care of these conditions, and consists in applying a flexible sheath 58, enclosing the flexible element from one end to the other, guiding it all through.

This flexible sheath is preferably made of spring wire closely wound, to produce a sheath or conduit which is extremely flexible, and at the same time is elastic, easily bent around, but constantly tending to resume its naturally straight condition when the opportunity is given.

On account of its function, flexible sheath 58 actually constitutes a connection between the lower part of the stand, and the upper part of the book-holding member running alongside of the device, as Figs. 1, 2, clearly show; and on account of its flexible nature, when the book-holding member is released, from catches 37, 38 by the action of control lever 39, this member can instantly fall to its inoperative position, shown in Fig. 4, sheath 58 forming into an easy curved, as shown, without any sharp bends. As part 23 is again raised to its operative position, sheath 58 resumes its straight condition of its own accord, without showing the least permanent deformation.

Sheath 58 is therefore a protective member for the flexible wire, which maintains it at all times free of entanglements or sharp bends, which insures its free and easy operation by guiding it throughout its length, and which adds to the appearance of the machine, at the same time causing no hindrance to its operation.

An important detail in the operation of the device, is the insertion and the removal of a note book, which must easily and readily be made. Also, it is important to design the device, and the means for holding the book in place, in a manner calculated to insure positive action at all times, and a firm hold on the book itself.

These details are substantially the same as those shown in my previous patent application. The operating mechanism, and frame 47, are mounted in a casing 65, which is pivotally mounted at one side of part 23, by means of a hinge member 66, having a longitudinal pivot 67. Said hinge is preferably of the spring type, being provided with a spiral spring 68, tending to maintain the casing in its open position, shown in Figs. 8, 13,

At the other side, the casing may be secured in position by a spring catch 69 engaging a pin 70. By pressing catch 69, the casing will be thrown open, and the entire surface of book-holder 23 will become exposed and accessible. Said part 23 has its lower edge upturned at 71, to provide a support for the book carrier 72, to which the book is attached in a suitable manner.

A short pin 73 preferably is provided, projecting from the surface of part 23, engaging a corresponding opening in the book carrier or plate 72 (not shown). Casing 65 being in its open position, the book-carrier, together with its attached book, is placed with its lower edge upon support 71, and is then swung against the surface of part 23, in the manner illustrated in Fig. 8; casing 65 is then closed, and the device is ready for operation. The object of pin 73 is to engage the plate 72 so as to prevent its upward shifting due to the force exerted against the book by the feeding member.

When part 23 is in its lower, or inoperative position, the book carried thereby is concealed from view, and it is necessary, in order to start transcribing, to raise part 23. Its upper edge is therefore turned rearwardly as at 74, forming a recess within which the tip of the fingers of the operator may be inserted to take hold of and to lift said part 23. At the same time, said upper edge forms a curved support for the overturned leaves of the book, 75.

The book is secured on to the plate or carrier 72 in any suitable manner; however, I prefer to adopt the arrangement shown in Fig. 7, where it appears that a note book 76, provided with binding clips 77 formed with a loop or eye 78, is used. Said loop or eye portion, which is transversal to the face of the book, projects from the binding edge about one-quarter of an inch, and provides means whereby the book may be suspended to the book carrier. The book carrier is formed with tubular portions 79, 80, at the top, between which loop or eye 78 may be inserted, after which a pin 81 may be inserted through said tubular portions and loops, establishing a connection between the book carrier and the book after the fashion of an ordinary hinge. The book remains thus suspended to the book carrier, said book carrier in its turn providing a metal to metal connection with the device. The book may be left connected to the book carrier while notes are being written, since the book carrier provides a stiff backing which greatly facilitates proper holding of the book.

To further facilitate the insertion of the book carrier in position, the sides of part 23 are formed with forwardly extending lugs 82, guiding the plate, 72, when the book carrier is set up as shown in Fig. 8.

The book is held in position by the pres-

sure exerted against it by the feeding member; this pressure being derived, indirectly, from the tension of spring 62, tending to wind up element 54 on drum 56. Furthermore, its leaves are prevented from fluttering, so that its front page is held flat and exposed to view, by a spring cross bar 83, pivotally attached to the sides of casing 65 by arms 84, and held pressed against the face of the book by a spring 85.

In its standard form, the device is held in position simply by inserting its base plate 21 under the feet of the typewriting machine; but it is obvious, that the device may be made, if desired, adapted for direct attachment to the frame of the typewriter itself, or else it may be made adapted to be supported on the desk in some other manner.

In my co-pending application No. 571,914, I have pointed out the fact that in operating this type of devices, it is desirable to feed a few lines at a time, and even half page at a time, leaving the copy stationary while the portion thus exposed is being transcribed. I have also explained how, on account of the relatively long feed required, if a circular feeding member of a small diameter is employed, it becomes necessary to so control the feeding member that a relatively short angular motion of the operating lever, is transformed into a relatively large angular motion of the feeding member, which might even have to rotate one or more revolutions.

This is the reason which has led me also in this case to use power transmitting means calculated to provide the necessary ratio between the first and the ultimate movers although it is obvious that also in this respect my device is susceptible of change in a number of ways.

The feeding member comprises, as stated, a shaft 43 carrying the contact member or members. In order to obtain a light construction, and at the same time good frictional contact and positive action, I prefer to use the construction shown, where a plurality of disc shaped members, designated by numerals 45, 45', 45'', 45''', are mounted on said shaft. Said disc shaped members are preferably made of rubber, or with a rubber peripherical section, and are formed with notches 87 causing their periphery to acquire an outline similar to that of a gear, composed of a number of radial prongs 88. The broken out line thus obtained, produces a yielding surface permitting to two or more of the prongs to engage the underlying surface at one time, and a good frictional contact becomes thus established.

In the foregoing description I have clearly set forth the construction and operation of my device; and in so doing I have endeavored to analyze the purpose of the various elements involved, rather than their specific form, being aware that similar functions may

be fulfilled by mechanical elements differently constructed and arranged. While the drawings represent the preferred embodiment of my invention, therefore, the same will have to be considered as intended for illustrative purposes only, and not in a limiting sense.

It is accordingly my intention to carry my invention into practice in any way or manner which considerations of design or manufacture may suggest, and which may enter, fairly, into the scope of the appended claims.

I claim:

1. In a device of the class described, the combination, with a note book comprising a plurality of superimposed sheets, means for holding the same in position, and feeding means adapted to successively engage and unfold the said sheets, of a carrier for said feeding means, adapted to hold the same in abutment with the surface of each succeeding sheet a relatively short distance from the folding edge thereof, said carrier being movable towards said book and away from the said folding edge, as the thickness of the book decreases.

2. In a device of the class described, the combination, with a holder for a note book, of feeding means for abutting against the outer surface of said book, and a carrier for said feeding means, pivotally mounted at a point above and behind the surface of said holder.

3. In a device of the class described, the combination, with a holder for a copy sheet, of feeding means adapted to abut against the surface of said sheet, a pivotally mounted carrier therefor, means for operating said feeding means, associated with said carrier, and controlling means therefor, holding said carrier and feeding means pressed against the surface of said sheet, while actuating the said operating means.

4. In a device of the class described, the combination, with a holder for a copy sheet and a feeding member abutting against the surface thereof, of a pivotally mounted carrier for said feeding member, a unidirectionally operative mechanism mounted on said carrier operating said feeding member, and a flexible element actuating said mechanism.

5. In a device of the class described, the combination, with a holder for a copy sheet and a feeding member abutting against the surface thereof, of a pivotally mounted carrier for said feeding member, a unidirectionally operative mechanism mounted on said carrier operating said feeding member, and means for actuating said mechanism, causing said carrier to move towards the surface of said sheet.

6. In a device of the class described, the combination, with a holder for a copy sheet and a feeding member abutting against the surface thereof, of a carrier for said feeding

- member, a pivotal attachment for said carrier, a pawl and ratchet mechanism operating said feeding member, mounted on said carrier eccentrically of said pivotal attachment, 5 and a flexible element actuating said pawl and ratchet mechanism.
7. In a device of the class described, the combination of a stand, a copy holding member mounted in telescopic relation thereto, an 10 operating mechanism carried by said copy holding member, a controlling mechanism therefor mounted on said stand, and flexible power transmitting means connecting said controlling and operating mechanisms, said 15 flexible means being of a length sufficient to permit shifting of said copy holding member to its extended position.
8. In a device of the class described, the combination of a stand, a copy holding member 20 mounted in telescopic relation thereto, an operating mechanism carried by said copy holding member, comprising a movable feeding member abutable against the surface of sheets carried by said copy holding member, 25 and adapted to move said sheets, a controlling mechanism therefor mounted on said stand, flexible power transmitting means connecting said controlling and operating mechanisms, and a flexible tubular guiding member 30 for said flexible means, said flexible means and guiding member being of a length sufficient to permit shifting of said copy holding member to its extended position.
9. In a device of the class described, the combination of a stand, a copy holding member 35 mounted thereon in telescopic relation thereto, a page turning mechanism carried by said copy holding member spring controlled means for maintaining said copy holding member in its extended position, an operating member, and an extensible operative connection 40 between said operating member and said mechanism.
10. In a device of the class described, the combination of a stand, a copy holding member 45 mounted thereon in telescopic relation thereto, a page turning mechanism carried by said copy holding member, spring controlled means for maintaining said copy holding member in its extended position, means 50 for operating said spring controlled means, to release said member, an operating member, and an extensible operative connection between said operating member and said mechanism.
11. In a device of the class described, the combination of a stand, a book holding member 55 mounted thereon in a telescopic relation thereto, a casing carried by said book holding member mounted on a longitudinal pivot at one side thereof, and a page turning mechanism mounted in said casing.
12. In a device of the class described, a book holding member, a casing mounted 60 thereon on a longitudinal pivot at one side thereof, a frame mounted within said casing on a horizontal pivot, a feeding member rotatably mounted in said frame, and an operating mechanism therefor, comprising elements 65 rotatably mounted on said frame at a point radially detached from said horizontal pivot.
13. In a device of the class described, a book holding member, a casing mounted thereon on a longitudinal pivot at one side thereof, a frame mounted within said casing on a horizontal pivot, a feeding member rotatably mounted in said frame, an operating mechanism therefor, comprising elements 70 rotatably mounted on said frame at a point radially detached from said horizontal pivot, and means under the control of the operator controlling said operating mechanism.
14. In a device of the class described, a stand, a book holding member mounted 75 thereon in a telescopic relation thereto, a casing carried by said book holding member mounted on a longitudinal pivot at one side thereof, a frame mounted within said casing on a horizontal pivot, a feeding member rotatably mounted in said frame, an operating mechanism therefor, means controlling said operating mechanism mounted on said stand, and a flexible power transmitting element 80 connecting said controlling to said operating means.
15. In a device of the class described, a stand, a book holding member mounted 85 thereon in a telescopic relation thereto, a casing carried by said book holding member mounted on a longitudinal pivot at one side thereof, a frame mounted within said casing on a horizontal pivot, a page turning mechanism mounted in said frame, means controlling said mechanism mounted on said stand, a flexible power transmitting element 90 connecting said controlling means to said mechanism, and a flexible tubular guiding element 95 for said flexible connecting element, said flexible connecting and guiding elements being of a length sufficient to permit shifting of said book holding member to its extended position.
16. In a device of the class described, a stand, a book holding member mounted 100 thereon in a telescopic relation thereto, a casing pivotally mounted on said book holding member, a page feeding member rotatably mounted in said casing, operating means therefor, means mounted on said stand controlling said operating means, a flexible power transmitting element connecting said controlling and operating means, and a flexible tubular guiding element for said flexible connecting element.
17. In a device of the class described, a stand, a book holding member mounted thereon in a telescopic relation thereto, a page turning mechanism mounted on said book holding member, controlling means therefor 115
18. In a device of the class described, a stand, a book holding member mounted thereon in a telescopic relation thereto, a page turning mechanism mounted on said book holding member, controlling means therefor 120
19. In a device of the class described, a stand, a book holding member mounted thereon in a telescopic relation thereto, a page turning mechanism mounted on said book holding member, controlling means therefor 125
20. In a device of the class described, a stand, a book holding member mounted thereon in a telescopic relation thereto, a page turning mechanism mounted on said book holding member, controlling means therefor 130

mounted on said stand, a flexible element connecting said controlling means to said page turning mechanism, a flexible tubular guiding element for said connecting element, said flexible connecting and guiding elements being of a length sufficient to permit shifting of said book holding member to its extended position, and releasable spring controlled means maintaining said book holding member in its extended position.

18. In a device of the class described, a stand, a book holding member mounted thereon in a telescopic relation thereto, a page turning mechanism mounted on said book holding member, controlling means therefor, a flexible element connecting said controlling means to said page turning mechanism, a flexible tubular guiding element for said connecting element, said flexible connecting and guiding elements being of a length sufficient to permit shifting of said book holding member to its extended position, releasable spring controlled means maintaining said book holding member in its extended position, and means under the direct control of the operator for operating said controlling means.

19. In a device of the class described, the combination, with a holder for a copy sheet, and a feeding member abutting against the surface thereof, of a pivotally mounted carrier for said feeding member, a unidirectionally operative mechanism mounted on said carrier operating said feeding member, and means actuating said mechanism.

20. In a device of the class described, the combination of a stand, a book holding member mounted thereon in a telescopic relation thereto, a casing pivotally mounted on said book holding member, and a page turning mechanism mounted in said casing.

21. In a device of the class described, the combination with a holder for a copy sheet, of a feeding member adapted to abut against the surface of a sheet carried thereby and a pivotally mounted carrier for said feeding member, said feeding member tending to remain in its position of abutment due to its own weight and to that of said carrier.

22. In a device of the class described, the combination with a holder for a copy sheet and a feeding member adapted to abut against the surface thereof, of a carrier for said feeding member, the combined weight of said feeding member and carrier tending to maintain said feeding member in its position of abutment, a mechanism operating said feeding member in the feeding direction, and manually operable means actuating said mechanism.

23. In a device of the class described, the combination with a holder for a copy sheet and a feeding member adapted to abut against the surface thereof, of a carrier for said feeding member, the combined weight of said

feeding member and carrier tending to maintain said feeding member in its position of abutment, a unidirectionally operative mechanism operating said feeding member in the feeding direction, and manually operable means actuating said mechanism.

24. In a device of the class described, the combination with a holder for a copy sheet and a rotatable feeding member abutting against the surface thereof, of an operating lever, a rotatable element controlled thereby and operative connections between said rotatable element and said feeding member, transmitting motion from the former to the latter at an increased angular ratio.

25. In a device of the class described, the combination with a holder for a copy sheet and a rotatable feeding member abutting against the surface thereof, of an operating lever, a unidirectionally operative mechanism controlled thereby, comprising a rotatable element, and operative connections between said rotatable element and said feeding member transmitting motion from the former to the latter at an increased angular ratio.

26. In a device of the class described, the combination of a stand, a holder for a copy sheet mounted thereon in a telescopic relation thereto, a casing movably mounted on said holder and a sheet feeding mechanism mounted on said casing.

27. In a device of the class described, the combination with a holder for a copy sheet and a feeding member adapted to abut against the surface thereof, of a carrier for said feeding member movably mounted on said holder, an operating mechanism mounted on said carrier actuating said feeding member, a flexible element actuating said operating mechanism, and manually operable means actuating said flexible element.

28. In a device of the class described, a stand, a copy holder mounted thereon forming an extensible and collapsible structure therewith, a page turning mechanism carried by said copy holder, a controlling mechanism therefor, and an extensible operative connection between said controlling and said operating mechanism.

29. In a device of the class described, a stand, a copy holder mounted thereon, forming an extensible and collapsible structure therewith, a page turning mechanism carried by said copy holder, a controlling mechanism therefor, and a flexible operative connection between said controlling and said operating mechanism.

30. In a device of the class described, a stand, a book holding member mounted thereon, forming an extensible and collapsible structure therewith, a casing movably mounted on said book holding member, and a page turning mechanism mounted in said casing.

31. In a device of the class described, a stand, a book holding member mounted there-

on, forming an extensible and collapsible structure therewith, a casing carried by said book holding member mounted on a longitudinal pivot at one side thereof, a frame

5 mounted within said casing on a horizontal pivot, a feeding member rotatably mounted on said frame, an operating mechanism therefor, means controlling said operating mechanism mounted on said stand, and an extensible operative connection between said controlling means and said mechanism.

10 32. In a device of the class described, a stand, a book holding member mounted thereon, forming an extensible and collapsible structure therewith, a casing pivotally mounted on said book holding member, a page turning mechanism mounted in said casing, and means under the control of the operator for actuating said mechanism.

15 33. In a device of the class described, the combination with a holder for a copy sheet, and a rotatable feeding member abutting against the surface thereof, of an operating lever, a unidirectionally operative mechanism, controlled thereby, comprising a rotatable element, and a gearing interposed between said rotatable element and said feeding member, transmitting motion from the former to the latter at an increased angular

20 30 34. In a device of the class described, the combination with an extensible and collapsible frame comprising a stationary and a movable member, a page turning mechanism mounted on said movable member and a controlling member, of a deformable actuating connection between said controlling member and said mechanism, said connection permitting movement of said movable member from

25 35 40 one of its extreme positions to the other, and being operative when said movable member reaches its extended position.

30 35 45 50 55 60 65 36. In a device of the class described, the combination, with a note book comprising a plurality of superimposed sheets folded in bulk to form an upper and a lower book section, and feeding means adapted to successively engage and unfold the said sheets, of means for mounting the said feeding means, causing the same to abut against the surface of each succeeding sheet a relatively short distance from the folding edge thereof, and causing said feeding means to be gradually inwardly displaced, lengthwise of said book, by relatively minute quantities, so as to substantially counterbalance the displacement of the folding edge of each sheet in relation to that of the next outer sheet.

60 65 70 75 80 85 90 95 100 105 110 115 120 125 130

turning movement in said carrier, causing said feeding means to press against the surface of said sheet.
